CLAIM

The ornamental design for a cover for a personal emergency medical alert device, as shown and described.

DESCRIPTION

FIG. 1 is a perspective view of a cover for a personal emergency medical alert device showing my new design on the front surface of the device with cutouts for an emergency button, a speaker, and a charger plug of the device; FIG. 2 is a front elevational view of the cover of FIG. 1; FIG. 3 is a left view of the cover of FIG. 1; FIG. 4 is a right view of the cover of FIG. 1; FIG. 5 is a back view of the cover of FIG. 1; FIG. 6 is a top view of cover of FIG. 1; and, FIG. 7 is a bottom view of the cover of FIG. 1.

The personal medical alert device is shown in broken lines for illustrative purposes only and forms no part of the claimed design.
